F. G. GIES

WASHING MACHINE

Filed Oct. 15, 1927

UNITED STATES PATENT OFFICE.

FRANK G. GIES, OF DETROIT, MICHIGAN, ASSIGNOR OF ONE-HALF TO LEONARD LESZCZYNSKI, OF DETROIT, MICHIGAN.

WASHING MACHINE.

Application filed October 15, 1927. Serial No. 226,274.

One of the primary objects of my invention is to provide a washing machine having an operating shaft extending into the tub and a seal which is positive to prevent leakage of water to the floor around the tub and does not require carefully made stuffing boxes.

More specifically my invention embodies a washing machine having a driving shaft extended into the tub and a flexible diaphragm like seal secured to the shaft and a portion of the tub in order to prevent leakage.

With the above and other objects in view, my invention consists in the arrangement, combination and construction of the various parts of my improved device as described in the specification, claimed in my claims and shown in the accompanying drawings, in which:

Fig. 1 is a view partly in section and partly in elevation of a washing machine embodying my invention.

Fig. 2 is a view taken on line 2—2 of Fig. 1.

Fig. 3 is a view taken on line 3—3 of Fig. 1.

I have shown a washing machine comprising a tub 5 having an integral piece 6 forming a portion of the bottom thereof and a separate piece 7 secured to the piece 6 by rivets 8 and forming the remainder of the bottom thereof. The piece 7 is somewhat drum shaped in formation and is provided with a central apertured boss 9 in which is fitted a bushing 10 having a flange 11 fitted on the top of the boss within the tub. Extended thru the bushing 10 is a shaft 12 which is provided with helical grooves 13 at its top and is secured to a member 14 by a nut 15 at its bottom. A connecting rod 16 is secured to the clevis 17 and pins 18 to the lower end of the member 14.

The connecting rod is secured at its lower end by a pin 19 to a worm gear 20, the connection being an eccentric one so that rotation of the gear will vertically reciprocate the rod. The gear 20 is meshed with a worm 21 provided on the shaft 22 mounted in suitable bearings of the base 23. The shaft 22 is driven thru a universal joint 24 by an electric motor 25. The motor 25 is bolted to a base member 26 as at 27 and the washing machine base member is likewise bolted as at 28 to the base 26.

The bushing 10 is held in fixed position by screwing a split nut 29 on the threads 30 of the boss 9. The bushing is provided with an upward extension which encloses the helix

13 and a pair of keys 31 are inserted in the extension and mesh with the helical groove 13. Each of the keys 31 is split into two sections which may be separated by shims 32 in order that the length of the keys may be adjusted. After the length has been adjusted the keys are secured in place by screwing a nut 33 into the upper end of the bushing 10. The nut may be held in fixed position by pins 34.

An agitator device comprising a central portion 35 and blades 36 is provided, the central portion engaging around the upper portion of the bushing 10 and keyed thereto as at 37 so as to rotate therewith. The agitator is held in fixed vertical position by resting on the flange 38 provided on the bushing 10.

A drain for the tub 5 is shown at 39 which drain may be opened and closed by means of a plug 40 on the end of a rod 41. The rod 41 is connected at its outer end as at 42 to a throw provided on the shaft 43 and operated by a handle 44.

A passage 45 connects the drain 39 with a space 46 which is provided between the bottom of the member 7 and flexible diaphragm 47 like piece 47. The latter piece is secured at its outer edges between the bottom of the member 7 and the top of the base piece 23 by a plurality of setscrews 48. The diaphragm is secured around the shaft 12 by placing its inner edge under the flange 58 of the member 14 and screwing the nut 49 on the threads 50 and against the lower face of the inner periphery of the diaphragm.

The nut 49 may be locked in place by a pin 90 or pins 51 extended thru openings therein into suitable aligned openings 52 in the member 14.

It will be readily apparent that rotation of the motor shaft 22 will cause reciprocation thru the connected parts of the shaft 12 and that reciprocation of the shaft 12, because of the connection of the keys 31 with the helix 13, will cause rotary reciprocation of the agitator blades 36. If any water finds its way around the flange 11 of the bushing 10 into the space 46 it will be held by the diaphragm 47 against falling to the floor. The diaphragm may be made of canvas, rubber or any other suitable water tight flexible material, preferably non-metallic in structure, so as to freely flex as the shaft 12 is reciprocated. When the tub is drained any water which may have collected in the space 46 will pass out thru the passage 45 and 110

drain 39. If an excessive amount of water should accumulate in the space 46 while the machine is in operation it may escape thru the opening 56 in the member 7 back into the tub. The opening 56 is normally maintained closed by a ball valve 53 seated therein and resiliently held by a spring finger 54 secured by a screw 55 to the bottom of the member 7.

10 It will be obvious that I have provided a machine which will successfully operate without leakage of water and which does not require expensive stuffing boxes.

It will be obvious that various changes 15 may be made in the arrangement, combination and construction of the various parts of my improved device without departing from the spirit of my invention and it is my intention to cover by my claims such changes 20 as may be reasonably included within the scope thereof.

What I claim is:

1. A washing machine comprising a tub and an agitator therein, a driver positioned 25 outside the tub, driving means connecting said driver and agitator, and a flexible member connected at one edge to a portion of the tub assembly and at another edge to a portion of the driving means and acting to 30 seal the tub against leakage around the driving means.

2. A washing machine comprising a tub and an agitator therein, a driver positioned outside the tub, driving means connecting 35 said driver and agitator, and a diaphragm like member connected at one edge to a portion of the tub assembly and at another edge to a portion of the driving means and acting to seal the tub against leakage around 40 the driving means.

3. A washing machine comprising a tub and an agitator therein, a driver positioned outside the tub, driving means connecting said driver and agitator, and a non-metallic diaphragm like member connected at one 45 edge to a portion of the tub assembly and at another edge to a portion of the driving means and acting to seal the tub against leakage around the driving means.

50 4. A washing machine comprising a tub and an agitator therein, a driver positioned outside the tub, a reciprocating member connecting the driver and agitator for driving the latter, a flexible member connected at one edge to said member and at another edge to a portion of the tub assembly and acting to seal the tub against leakage around the member.

55 5. A washing machine comprising a tub and an agitator therein, a driver positioned outside the tub, a reciprocating member connecting the driver and agitator for driving the latter, a diaphragm like member connected at one edge to said member and at another edge to a portion of the tub assem-

bly and acting to seal the tub against leakage around the member.

6. A washing machine comprising a tub and an agitator therein, a bearing in the bottom of the tub, a shaft in said bearing connected at one end with the agitator and having its other end extended thru the bottom of the tub, driving means connected with the latter end of the shaft for reciprocating it and the agitator and a flexible member connected at one edge to the shaft and at another edge to a portion of the tub assembly and adapted to catch any leakage from the tub around the shaft bearing.

7. A washing machine comprising a tub 80 and an agitator therein, a bearing in the bottom of the tub, a shaft in said bearing connected at one end with the agitator and having its other end extended thru the bottom of the tub, driving means connected with the latter end of the shaft for reciprocating it and the agitator, a flexible member connected at one edge to the shaft and at another edge to a portion of the tub assembly 85 and adapted to catch any leakage from the tub around the shaft bearing, and a relief device permitting liquid escape from the space between the tub bottom and flexible member when a predetermined amount of liquid has been collected in the space.

8. A washing machine comprising a tub and an agitator therein, a bearing in the bottom of the tub, a shaft in said bearing connected at one end with the agitator and having its other end extended thru the bottom 100 of the tub, driving means connected with the latter end of the shaft for reciprocating it and the agitator, a flexible member connected at one edge to the shaft and at another edge to a portion of the tub assembly and adapted 105 to catch any leakage from the tub around the shaft bearing, and a relief device permitting liquid escape from the space between the tub bottom and flexible member when a predetermined amount of liquid has been collected 110 in the space, said device comprising a valve opening thru the tub bottom.

9. A washing machine comprising a tub and an agitator therein, a bearing in the bottom of the tub, a shaft in said bearing connected at one end with the agitator and having its other end extended thru the bottom of the tub, driving means connected with the latter end of the shaft for reciprocating it and the agitator, a flexible member connected at one edge to the shaft and at another edge to a portion of the tub assembly and adapted 120 to catch any leakage from the tub around the shaft bearing, and means for draining the space between the bottom of the tub and the 125 flexible member.

10. A washing machine comprising a tub and an agitator therein, a bearing in the bottom of the tub, a shaft in said bearing connected at one end with the agitator and hav- 130

- ing its other end extended thru the bottom of the tub, driving means connected with the latter end of the shaft for reciprocating it and the agitator, means between the agitator and shaft for translating vertical reciprocation of the shaft into rotary reciprocation of the agitator, and a flexible member connected at one edge to the shaft and at another edge to a portion of the tub assembly and adapted to catch any leakage from the tub around the shaft bearing.
11. A washing machine comprising a tub and an agitator therein, a bearing in the bottom of the tub, a shaft in said bearing connected at one end with the agitator and having its other end extended thru the bottom of the tub, driving means connected with the latter end of the shaft for reciprocating it and the agitator, means between the agitator and shaft for translating vertical reciprocation of the shaft into rotary reciprocation of the agitator, said means comprising a helix on one of the two and a member operatively engaging the helix on the other, and a flexible member connected at one edge to the shaft and at another edge to a portion of the tub assembly and adapted to catch any leakage from the tub around the shaft bearing.
12. A washing machine comprising a tub and an agitator therein, an apertured boss in the bottom of the tub, a bushing in the aperture having a flange seating on the top of the boss, a nut on the boss pressing the flange against the boss, a shaft in the bushing extending from the inside to the outside of the tub, a driver for the shaft outside the tub and a connection joining the shaft to the agitator within the tub, a seal for the shaft comprising a flexible member secured around the shaft beneath the tub and extending and secured to a portion of the tub assembly.
13. A washing machine comprising a tub and an agitator therein, an apertured boss in the bottom of the tub, a bushing in the aperture having a flange seat on the top of the boss, a nut on the boss pressing the flange against the boss, a shaft in the bushing extending from the inside to the outside of the tub, a driver for the shaft outside the tub and a connection joining the shaft to the agitator within the tub.
14. A washing machine comprising a tub and an agitator therein, an apertured boss in the bottom of the tub, a bushing in the aperture having a flange seat on the top of the boss, a nut on the boss pressing the flange against the boss, a shaft in the bushing extending from the inside to the outside of the tub, a driver for the shaft outside the tub and a connection joining the shaft to the agitator within the tub, and a seal for the shaft comprising a flexible member secured around the shaft beneath the tub and extending and secured to a portion of the tub assembly.
